FIG. 1

UNITED STATES PATENT OFFICE

2,357,256

APPLICATOR

John N. Eidl, Elyria, Ohio

Application August 20, 1941, Serial No. 407,675

4 Claims. (Cl. 15—133)

This invention relates to improvements in applicators of that type adapted for ready attachment to the threaded nipple of a collapsible paste tube the latter functioning as a handle and a convenient means for supplying a paste, such as shaving cream, to discharge ports on the applicator. Heretofore, in applicators of this general type, the shaving cream is extruded through openings and spread over the face by bodily movement of the applicator. The quantity of cream supplied is greatly in excess of that required to effectively soften the beard due to the fact that the cream is discharged in direct proportion to the pressure exerted upon the collapsible tube and this results in waste as well as in uneven application.

One of the objects of the present invention is therefore, to provide an applicator in which a definite measured quantity of cream is supplied from the collapsible tube on which it is mounted and, thereafter, that measured quantity applied to the face in a smooth even layer.

Another object of the present invention is to provide an applicator having relatively movable parts extended by the introduction of cream under pressure from the collapsible tube and the cream discharged therefrom through outlet ports by relative contraction of the parts effected by the counteracting resistance afforded by the face.

Another object of the present invention is to arrange the relatively movable parts in telescopic relation whereby the size of the applicator is maintained at a minimum without decreasing the efficiency.

Another object of the present invention is to provide the applicator with a cream receiving chamber capable of being submerged in hot water to heat the cream if desired before application to the face.

Another object of the present invention is to so shape the spreader plate of the applicator that the cream will not pile up or slop over the plate when passing over the face.

Another object of the present invention is to provide an applicator of light weight, compact, simplified construction embodying sound engineering principles of operation, efficient and inexpensive to manufacture and assemble.

With the objects above indicated, and other objects hereinafter explained in view, my invention consists in the construction and combination of elements hereinafter described and claimed.

Referring to the drawing:

Figure 1 is a side elevational view of the ap-

plicator embodying the invention mounted upon a collapsible tube and substantially full size.

Figure 2 is a side elevational view of the applicator with portions in section to more clearly illustrate the invention and shown on an enlarged scale.

Figure 3 is an end elevational view of the applicator shown in Figure 2, looking at the discharge end, and having portions broken away to more clearly illustrate details of the construction.

Figure 4 is a fragmentary transverse sectional view taken substantially along line 4—4 in Figure 2 and showing details of spreader plate.

Figure 5 is a transverse sectional view of a modified form of applicator taken substantially along the dot and dash line 5—5 in Figure 2.

Figure 6 is a transverse sectional view of a further modified form of applicator taken substantially along the dot and dash line 6—6 in Figure 2.

Figure 7 is a fragmentary longitudinal vertical sectional view showing a modification of the sealing means.

Figure 8 is a fragmentary longitudinal vertical sectional view of the spreader plate showing a further modification.

In the drawing I have illustrated one embodiment of the invention but it should be understood that other adaptations may be made, as will be obvious to those skilled in the art, and the invention is, therefore, in no manner so restricted.

The applicator 10 comprises relatively movable members 11 and 12 operatively associated in any desirable manner for the purpose intended but for advantages hereinafter set forth best results are attained when telescopically disposed. The applicator has been made of metal and satisfactorily operated but it may be desirable to employ plastic material and the design and construction illustrated affords such use without necessitating material changes.

The outer member 11 is of tubular form substantially square in cross section, as more clearly shown in Figure 3, and of suitable length. The inner end of the tubular member 11 has an inwardly extending marginal flange 13 while the outer end, in side elevation, terminates in an angular plane surrounded by an outwardly extending flared portion 14, as more clearly shown in Figure 2. A spreader plate 15 extends across the open end of the tubular member 11 and has its marginal edge secured to the adjacent face of the flared portion 14 after the member 12 is inserted in a manner to be later described. The outer

face of the spreader plate 15 is bulged outwardly on a suitable curvature so as to pass freely over a person's face and prevent piling up of the dispensed cream. Any suitable opening may be provided in the spreader plate 15 to afford discharge of the cream therethrough but experiments have shown that a pair of relatively large openings 16 of substantially equal area and spaced relatively close together affords best results. A cover member 17 fits over the spreader plate 15 when not in use and is detachably connected to the adjacent free edges of the flared portion 14.

The inner member 12 is likewise, of tubular form substantially square in cross section, as more clearly shown in Figure 3, and slidably disposed within the opening formed by the marginal flange 13 on the outer tubular member 11. Adjacent the outer end of the tubular member 12 is an outwardly extending peripheral flange 18 the outer face of which is slidably engageable with the inner peripheral wall of the tubular member 11 thereby providing, with the flange 13, suitably spaced bearings to insure free sliding movement of one within the other. To prevent any of the cream from working its way onto the outer exposed surface of the tubular member 12 a packing ring 19 is suitably secured upon the free end of the latter in abutment with the adjacent face of the flange 18 and sealingly but slidably engageable with the inner peripheral surface of the tubular member 11, the ring being of any suitable material. The inner end of the tubular member 12 projects a suitable distance beyond the inner end of the tubular member 11 and is closed by a cup-shaped cap 20 the annular wall of which encircles and is secured to the outer adjacent face of the tubular member 12. This cap 20 is, likewise, secured after the tubular member 12 has been disposed within the tubular member 11 to afford assembly. The end wall of the cap 20 is provided with an axially disposed interiorly screwthreaded opening 21 of such size as to permit its removable mounting upon a nipple of standard size provided on collapsible tubes 22.

A modified form of seal is shown in Figure 7 wherein the flange 18 extends forwardly to the front of the tubular member 12 and is provided with a centrally disposed peripheral groove 18' in which the packing ring 19 is secured.

Modifications of the cross sectional shape of the tubular members 11 and 12 are shown in Figures 5 and 6, the former being rectangular and the latter round, the numerals designating corresponding elements prefixed by one or two hundred as the case may be thus necessitating no additional description. In Figure 8 a modification of the spreader plate 15 is shown wherein the outer surface is covered by a layer of cloth such as felt or the like to assist in spreading the cream over the face.

In adapting the applicator for use the cap 20 is threadably mounted upon the discharge nipple of a collapsible tube of shaving cream and is preferably so retained until the cream has been completely used. With the cover member 17 in place upon the spreader plate 15 the tube is squeezed by the hand in the usual manner causing cream under pressure to be discharged from the nipple and flow into the inside of the tubular members 12 and 11 respectively until the space is completely filled. The flow of cream is resisted by the presence of the cover plate 17 and by reason of the cream being introduced under pressure the tubular member 11 is moved outwardly until the flange 13 engages the flange 18 at which time the desired quantity of cream has been supplied

in the applicator. The cover member 17 is next removed thus exposing the discharge openings 16 in the spreader plate 15 and the latter is then run over the bearded face. A slight pressure is exerted between the spreader plate and face tending to force the tubular member 11 inwardly which again exerts a pressure causing the cream in the applicator to pass through the openings 16 and onto the face in an even and smooth manner. When the outer tubular member 11 has moved inwardly until the flange 13 abuts the end of the annular wall on the cap 20 a predetermined quantity of cream has been applied to the face in an efficient and simple manner and the beard may then be removed by shaving in the usual manner. The operation is repeated for each new application and in the event that some may desire the cream to be warmed before being applied, the applicator can be submerged in warm water to raise the temperature of the cream. The applicator is so constructed that the usual messiness accompanying the application by hand is entirely eliminated.

While I have described the preferred embodiment of the invention it is to be understood that I am not to be limited thereto inasmuch as changes and modifications may be resorted to without departing from the spirit of the invention as defined in the appended claims.

What is claimed is:

1. An applicator for distributing shaving cream or the like to the face from a collapsible tube comprising: a pair of relatively movable members operatively connected for sliding movement and having communicating passageways therein; one of said members being attachable to the discharge nozzle of a collapsible tube to afford communication with its passageway; said tube being adapted to function as a handle and a source of supply; and the other of said members having a closed outer end adapted for sliding engagement with the face to be coated, said closed end being provided with a discharge opening affording communication with its passageway; said members being relatively extended a predetermined distance by introduction into the passageways of cream under pressure from the tube and thereafter relatively contracted by a force applied to the closed end during its engagement with the face to effect discharge of the cream through the discharge opening from the passageways.

2. An applicator for distributing shaving cream or the like to the face from a collapsible tube comprising: a member having a passageway therein and a communicating inlet opening adapted for connection with the discharge nozzle of a collapsible tube; said tube being adapted to function as a handle and a source of supply a second member operatively mounted on said first mentioned member for relative sliding movement in opposite directions and having a cream receiving chamber therein in communication with said passageway, said second member being provided with a spreader plate at its outer end for sliding engagement with the face and having an opening therethrough affording communication with said chamber whereby the cream may be discharged; and means on said members for limiting their relative sliding movement in both directions; said members being relatively extended to a predetermined distance by introduction into the chamber of cream under pressure from the tube and thereafter relatively contracted by a force applied to the closed end during its engagement with the face to effect discharge of the

cream through the discharge opening from said chamber.

3. An applicator for distributing shaving cream or the like to the face from a collapsible tube comprising: a member having a passageway therein and a communicating inlet opening adapted for connection with the discharge nozzle of a collapsible tube; said tube being adapted to function as a handle and a source of supply; a second member operatively mounted on said first mentioned member for relative sliding movement in opposite directions and having a cream receiving chamber therein in communication with said passageway; a spreader plate secured to the outer end of said second mentioned member and having a curved outer surface for sliding engagement with the face, said plate having an opening therethrough affording communication with said chamber whereby the cream may be discharged; and means on said members for limiting their relative sliding movement in both directions; said members being relatively extended a predetermined distance by introduction into the chamber of cream under pressure from the tube and thereafter relatively contracted by a force applied to the closed end during its engagement with the

face to effect discharge of the cream through the discharge opening from said chamber.

4. An applicator for distributing shaving cream or the like to the face from a collapsible tube comprising: an inner tubular member having a closed rear end provided with an inlet opening adapted for connection with the discharge nozzle of a collapsible tube; said tube being adapted to function as a handle and a source of supply; the outer tubular member slidably mounted on said inner tubular member and having a closed outer end adapted for sliding engagement with the face to be coated, said closed outer end having an opening therethrough to afford discharge of the cream; and means on said tubular members for limiting their relative sliding movement in both directions; said members being relatively extended a predetermined distance by introduction into the chamber of cream under pressure from the tube and thereafter relatively contracted by a force applied to the closed end during its engagement with the face to effect discharge of the cream through the discharge opening from said tubular members.
